WILLIAM LLOYD, OF DRIFTON, PENNSYLVANIA.

AUTOMATIC STOKER.

1,330,641.

Specification of Letters Patent.

Patented Feb. 3, 1920.

Application filed December 2, 1913. Serial No. 804,255.

To all whom it may concern:

Be it known that I, WILLIAM LLOYD, a citizen of the United States of America, and residing at Drifton, in the county of Luzerne 5 and State of Pennsylvania, have invented a certain new and improved Automatic Stoker, of which the following is a specification.

My invention relates to automatic stokers for furnaces and particularly to stokers of 10 the traveling grate type developed by Eckly B. Coxe. The present invention provides certain specific improvements therein, pointed out in the following description and illustrated in the accompanying drawing in 15 which,

Figure 1 is a longitudinal section through portion of a furnace showing my improved stoker partially in section;

Fig. 2 is an enlarged elevation partially in 20 section of portion of the grate;

Fig. 3 is a broken plan of a portion of the grate bar with certain portions removed;

Fig. 4 is a broken side elevation of the same showing some of the grate bar keys in 25 position;

Fig. 5 is a cross section through the grate bar on the line 5—5 of Fig. 3;

Fig. 6 is a plan of one of the keys carried by the grate bar;

Fig. 7 is a cross section on line 7, Fig. 6, 30 through one of the keys;

Fig. 8 is a side elevation of the expansion key;

Fig. 9 is a longitudinal section on line 9, 35 Fig. 3, through portion of a grate bar but showing the expansion key and adjacent keys in position;

Fig. 10 is a longitudinal section through one of the grate bars and adjacent masonry 40 portions of the side walls of the furnace.

Referring to the drawings and particularly to Fig. 1 thereof, the stoker to which the present invention relates is here shown arranged to fire a water tube boiler. The 45 stoker, generally represented by the reference A, receives coal from the hopper B and travels slowly the length of the fire chamber under drive of the worm gear C which in turn drives the sprocket D around which the 50 chain supported grate passes. The air blast passing upward through the grate bars of the stoker carries the products of combustion to the boiler tubes E and thence to the stack (not shown) in a well understood manner. The exhausted fuel or ash is discharged to the dump chute F as the grate passes around the sprocket D.

Turning to Figs. 2, 3, and 4, the stoker comprises a series of transverse grate bars, each comprising relatively heavy end blocks 60 201—202, and an intermediate depressed web 20, which constitutes the body of the bar and carries a bank of keys (hereinafter described) forming the grate bar top, on which the fuel is supported. Each end block of the 65 grate bar has a downwardly extending chain lug 22 which passes through a link in one of the customary side chains 21 and is secured thereto by a bolt 23. These lugs 22 may be cast integral with the end blocks of the grate 70 bars, or they may be secured thereto as shown, by means of bolts 24 with countersunk heads. One of the end blocks, viz., 201, is provided, on its upper face, with a shoulder 75 25 which forms the marginal support of the fuel bed carried by the grate, while the portion of the end block extending outward beyond the shoulder, passes beneath the masonry work at the side of the fire chamber, which thus protects the ends of the bar and 80 the subjacent chains from the heat of the fire. The other end block 202 has no shoulder, but its upper face is substantially flat, and the expansion key 27 (hereinafter described) rides thereon. Both end blocks are 85 provided with rearwardly extending aprons 41^a, and the forward margins of the blocks are recessed to accommodate like aprons on the end blocks of the adjacent bar (see Fig. 2) corresponding in this particular to the 90 outline of the grate bar keys. The apron of the end block 202 is recessed at 26 to accommodate the apron of the expansion key 27. The depressed key-supporting web, which extends between the end blocks, is perforated, as at 28, to permit the upward flow of 95 air from the blast to the fuel bed resting on the keys. On this web is formed or secured a skeleton dovetail or undercut rib 29, which extends the major portion of the length of 100 the bar. Elongated apertures 30 of the rib communicate with subjacent perforations in the web to admit the blast as freely as possible to the portion of the fuel bed overlying the rib.

The fuel-supporting surface of the grate is formed by successive banks of grate bar keys 31, one bank being carried by each grate bar. In the lower margins of the keys are undercut or dovetail recesses 32 which engage the ribs 29 of the grate bars. The keys of a bank are mounted on a bar by placing each key successively in alignment with the rib 29 at the hiatus, 33 in the latter, and then

sliding the key onto the rib lengthwise of the bar. After the rib 29 has been thus filled, the key bank is completed by adjusting the expansion key 27.

5 The expansion key comprises a shoulder 34 which corresponds to the shoulder 25 of the end block 201 at the opposite end of the bar and forms, in like manner, a marginal support for one side of the fuel bed. This 10 shoulder rides upon the upper surface of the flat end block 202 of the bar, and the body of the key is recessed to permit it to slide thus lengthwise of the bar. The outer end of the block 202 beyond the expansion 15 key 27 passes under the masonry work of the fire chamber in like manner as the outer end of the block 201. The apron 35 of the key rests in the recess 26 in the end block above mentioned and corresponds in curvature to the apron 41^a of the end block and to the apron of the key bank.

Inasmuch as the rib 29 of the grate bar does not extend into the space 33, it is substituted at this point by a bolt 29^b passing 20 through the hole 36 in the grate bar and having a head 29^a of dovetail contour, corresponding to that of the rib 29. The head of the bolt is first passed into the undercut groove in the lower margin of the expansion 25 key, and the latter then lowered into position, the shank of the bolt passing through the hole 36 in the bar. A nut 37, screwed onto the lower end of the bolt below the bar, holds the head 29^a firmly in position, 30 while leaving the expansion key free to slide thereon lengthwise of the bar.

Against the outer face of the expansion key bears a plunger 38 passing horizontally through the end block 202. On the stem 40 of this plunger is coiled a spring 39 placed under tension by the abutment screw 40 threaded into the tapped outer end of the plunger hole in the end block. The pressure of this plunger against the expansion key 45 assures the close contact of the keys in the bank, while, at the same time, permitting the expansion of the key bank under the heat of the fire bed and the contraction thereof as it cools on its return travel. This 50 feature is one of considerable importance when burning fine fuel, since the play which would otherwise be necessary between the keys to compensate their expansion when heated, would result in the working travel 55 of the grate being started with the keys more or less separated, and the fine fuel would fall between them and choke the air passages, thus impairing the efficiency of the grate.

60 The keys employed to form the mid portion or body of the key bank, also present certain features of novelty. One of the principal improvements is found in the apron 41 at the rear or following end of each key. This apron is extended rear-

wardly beneath the forward key of the succeeding bank a distance such that, when the key banks separate as they round the sprocket D at the end of the working travel of the grate, the rear edge of the apron 70 underlies the forward edge of the following key, so that the ash which falls between the key banks as they separate drops upon the apron and is thus kept from entering the air spaces of the inverted grate bars below 75 and choking them. The apron is preferably concaved to form a trough for the reception of the ash and keeps the latter from scattering, as above stated. The end blocks of the bar are also provided with aprons 41^a 80 which register with those of the key banks, thus making a continuous ash trough not only across the entire width of the fuel-supporting area of the grate, but also beyond the ends of this area. 85

A second feature of improvement is found in the longitudinal arching of the upper faces 42 of the keys. This has the effect of forming an uneven surface for the grate, so that it exerts a drag on the fuel at the bottom of the hopper B. It is found that, with the key banks thus shaped, no stirrer or other device is required to insure the proper feed of the coal to the grate as has been heretofore required when using fine coal 95 and the flat keys heretofore commonly employed. 90

A third feature of improvement is found in the transverse slots 43 in the upper faces of the keys. These slots have the triple 100 function of (a) forming a serrated grate surface, which, combined with the arched contour of the keys, insures a "grip" upon the coal by the grate as it travels beneath the hopper and causes a steady and even feed to the grate; (b) distributing the air to the fuel supported on the tops of the keys, since the slots extend completely across the latter and thus communicate with the air channels 44 between the keys—incidentally, as to this feature, these air channels serve to cool the surface of the keys and thus minimize the heat injury thereto; (c) permitting the expansion or contraction of the upper surface of the keys without material longitudinal distortion. The binding between longitudinally adjacent key banks which sometimes occurs as a result of longitudinal expansion, is thus obviated, and it is possible to fit the juxtaposed ends of the keys of adjacent 110 115 banks closer together than has been possible heretofore when the longitudinal expansion of the keys has had to be taken into consideration. This is a feature of value in handling fine coal, since where the banks must be spaced apart to provide for this expansion, the coal sifts in between the keys and is either lost or obstructs the air passages. 120

Another feature of improvement in the keys is found in the side construction there- 130

of, by which channels are afforded for the passage of air to the upper surface of the keys. One side 45 of each key is formed with a flat vertical face. The other side 46 5 of the key is so inclined that the blast passage afforded between it and the flat face of an adjacent key, widens downward from the fuel-supporting surface of the grate. From this side of the key project spacing 10 studs 48, the outer ends of which lie in a vertical plane and bear against the flat side of the adjacent key to form the blast passage 44. It will be noted that the apron 41 is provided with a flange 49 on the same 15 side of the key as the studs 48, so that this apron is continuous from one side of the bar to the other, and no interstice is permitted for the possible escape of ash between the keys into the bars below as the grate passes 20 over the sprocket D.

The air blast is supplied to the fuel on the grate from a wind box W which is arranged between the upper and lower reaches 25 of the grate and is divided by two transverse partitions 57 and 58 into three blast chambers, each of which has an opening 59, 60, or 61, respectively, for the admission of the air blast. Inasmuch as it is desirable to supply the air at different pressures to 30 the areas of the fuel bed above each chamber, it is necessary to provide sealing means which prevents leakage between the chambers over the tops of the partitions 57 and 58. For this purpose, the partitions are 35 provided with horizontal sealing plates 62-63, upon which the fins 64 of the grate bars rest and across which they travel as the grate bar advances. Similar sealing plates 65-66 at the opposite ends of the wind 40 box coöperate with the grate bar fins in like manner to prevent air leakage at these points. In order to render the seal effectual at all times, each of the sealing plates is of such width in the direction of travel of 45 the grate that before one of the grate bars has passed thereover, the succeeding bar engages the same and forms the desired seal.

In furnaces in which large coal is used, it is of no particular advantage to use small 50 keys. Certain features of construction herein described may nevertheless be advantageously incorporated in the keys employed, whatever their particular design or size,—notably the apron 41 for catching the 55 ash as the key banks separate on rounding the sprocket at the end of their working travel. In the appended claims, the word key is used therefore in a sense broad enough to cover keys of any suitable construction, such for instance, as that of the so-called grate top plates of the Van Vleck 60 Patent 1,063,288.

The present construction is particularly efficient in dealing with very fine coal, since 65 the air blast passing up through the grate

bars is uniformly and evenly distributed to the grate surface through the interstices between the keys and the cross channels in the upper faces of the latter. The smaller grades of buckwheat coal have been successfully burned on the present grate, while due to the novel arched construction of the keys and their serrated surfaces, there has been no difficulty with the feed. The fire burns evenly at the mid portion of the 70 bed as well as at the edges. Again, the ash is cleanly dumped to the discharge chute without falling between the banks of the keys by reason of the aprons 41. The blast distribution has been rendered effective by 75 the sealing plates and the coöperating ribs on the grate bars, inasmuch as the latter maintain their shape without warping, by reason of the fact, on the one hand, that the heat of the fire bed is lifted well above 80 them, and, on the other hand, they are constantly cooled from below by the upward flow of the blast.

Various modifications in detail will readily occur to those skilled in the art, 90 which do not depart from what I claim as my invention, and I do not limit myself to the illustrative details shown in the accompanying drawings and above described.

I claim as my invention:—

1. In an automatic stoker, an endless traveling grate comprising cross bars and on each bar a bank of keys, the keys of each bank being spaced apart at their coal-supporting faces to admit air from below to the 100 superposed coal bed but having at their rear ends, in the direction of the working travel of the grate, contiguous imperforate aprons underlying, in their extreme angular position, the forward ends of the keys of the following bank and forming a continuous transverse apron which serves to catch the ash falling between the adjacent banks of keys as their adjacent ends separate at the 105 end of the working travel of the grate. 110

2. In an automatic stoker, an endless traveling grate comprising cross bars and on each bar a bank of keys, the keys of each bank being spaced apart at their coal supporting faces to admit air from below to the 115 superposed coal bed but having at their rear ends, in the direction of the working travel of the grate, contiguous imperforate aprons underlying, in their extreme angular position, the forward ends of the keys of the following bank and forming a continuous transverse apron which serves to catch the ash falling between the adjacent banks of keys as their adjacent ends separate at the 120 end of the working travel of the grate, said apron 125 being concaved to form a receiving trough for the ash.

3. In an automatic stoker, an endless traveling grate comprising cross bars and on each bar a bank of keys, each of said 130

- keys having a vertical side wall, the opposite side wall being inclined outwardly from bottom toward the top of the key, studs projecting laterally from said inclined wall and adapted to space the key from the vertical wall of the adjacent key, together with transverse grooves in the upper face of the key opening to the space thus formed between adjacent keys.
10. 4. In an automatic stoker, an endless traveling grate comprising cross bars and on each bar a bank of keys, each of said keys having a vertical side wall, the opposite side wall being inclined outwardly from bottom toward the top of the key, studs projecting laterally from said inclined wall and adapted to space the key from the vertical wall of the adjacent key, together with transverse grooves in the upper face of the key opening to the space thus formed between adjacent keys, together with an apron, at the rear end of the key, in the direction of the working travel of the grate, underlying the forward end of the corresponding key in the following bank, said apron forming with the aprons of the remaining keys of the bank a continuous following apron adapted to catch the ash falling between adjacent banks of keys as their adjacent ends separate at the end of the working travel of the grate.
15. 5. In an automatic stoker, an endless traveling grate comprising perforated cross bars each having a dovetailed rib on its upper face, said rib being centrally apertured to permit the upward flow of the blast therethrough together with a series of keys mounted on said rib, each of said keys having a dovetailed recess in its lower portion adapted to fit said rib, lateral studs spacing said keys apart to admit the blast to the superposed coal bed, and at its rear end, in the direction of the travel of the grate, an apron contiguous with the aprons of juxtaposed keys and forming a continuous apron underlying the forward end of the following bank of keys and serving to catch the ash falling between the banks on the separation of their adjacent ends at the end of the working travel of the grate.
20. 6. In an automatic stoker, an endless traveling grate comprising a series of grate bars each having a fuel supporting face apertured to afford blast passages and an imperforate following apron underlying, in its extreme angular position, the forward edge of the fuel-supporting surface of the succeeding grate bar and the supporting surface of the apron being concaved to form a trough serving to catch the ash falling between adjacent bars as their juxtaposed edges separate at the end of the working travel of the grate.
25. 7. In an automatic stoker, an endless traveling grate comprising cross bars, a plurality of keys mounted transversely

slidable on each cross bar, and means carried by each bar outside the fire zone for maintaining the keys thereon constantly juxtaposed irrespective of expansion and contraction.

8. In an automatic stoker, an endless traveling grate comprising cross bars, a plurality of keys mounted transversely slidable on each cross bar, an expansion key on each bar and spring means carried by the bar outside the fire zone and bearing against said expansion key to press the same against the keys on said bar and thus to maintain the same juxtaposed irrespective of contraction and expansion.

9. In an automatic stoker, an endless traveling grate comprising cross bars, a plurality of keys mounted transversely slidable on each cross bar, an expansion key on each bar, a plunger passing through the end of the grate bar and bearing against said expansion key, a screw plug in the end of the bar and a spring interposed between said plug and plunger to force the latter against the expansion key, for the purpose described.

10. In an automatic stoker, an endless traveling grate comprising cross bars, an undercut rib extending partially the length of the upper face of each bar, a plurality of keys slidably engaged upon said rib, an expansion key, an independent undercut rib segment on which said expansion key is adapted to slide and means for fastening said rib segment in position after the keys have been adjusted upon the rib extending longitudinally of the bar.

11. In an automatic stoker, an endless traveling grate having a transverse grate bar with end blocks and an intermediate depressed section, means for mounting grate bar keys in said depressed section, one of said end blocks having a raised portion adjacent the depressed section to form a marginal support for the fire bed, while the portion of the end block beyond said raised portion extends beneath the masonry of the fire box wall when the grate is installed.

12. In an automatic stoker, an endless traveling grate having a transverse grate bar with end blocks and an intermediate depressed section, means for mounting grate bar keys in said depressed section, an expansion key having a shoulder sliding on one of said end blocks and forming a marginal support for the fire bed, while the portion of the end block beyond said expansion key extends beneath the masonry of the fire box wall when the grate is installed.

13. In an automatic stoker, an endless traveling grate comprising grate bars, a plurality of keys arranged on each grate bar, each of said keys comprising an elongated solid body having transverse serrations in its fuel-supporting face to admit

air from lateral blast passages to the fuel on the face of the key.

14. In an automatic stoker, an endless traveling grate comprising grate bars, a plurality of keys arranged on each grate bar, each of said keys comprising an elongated solid body affording a fuel-supporting surface, means for spacing said surface from a laterally juxtaposed key on said cross bar to afford a blast passage, and a rearward extension of said key body forming an imperforate apron of a width greater than the fuel-supporting surface of the key and adapted to meet the edges of corresponding extensions on laterally juxtaposed keys to afford a continuous imperforate apron, for the purpose described.

15. In an automatic stoker, an endless traveling grate comprising grate bars, a plurality of keys arranged on each grate bar, each of said keys comprising an elongated solid body affording a fuel-supporting surface, means for spacing said surface from a laterally juxtaposed key on said cross bar to afford a blast passage, and a rearward extension of said key body forming an imperforate apron of a width greater than the fuel-supporting surface of the key and adapted to meet the edges of corresponding extensions on laterally juxtaposed keys to afford a continuous imperforate apron, said apron being curved to the shape of the forward end of the following key.

16. In an automatic stoker, an endless traveling grate comprising grate bars, a plurality of keys arranged on each grate bar, each of said keys comprising an elongated solid body affording a fuel-supporting surface, means for spacing said surface from a laterally juxtaposed key on said cross bar to afford a blast passage, and a rearward extension of said key body forming an imperforate apron of a width greater than the fuel-supporting surface of the key and adapted to meet the edges of corresponding extensions on lateral juxtaposed keys to afford a continuous imperforate apron, said apron resting upon the cross bar of the grate.

17. In an automatic stoker, an endless traveling grate comprising grate bars, a plurality of keys arranged on each grate bar, each of said keys comprising an elongated solid body, spacing studs on one side of said body and a flange (49) at one end of said key and extending laterally from the body the same distance as the studs.

18. In an automatic stoker, an endless traveling grate comprising grate bars, a plurality of keys arranged on each grate bar, each of said keys comprising an elongated

body, spacing studs and an end flange (49) projecting from one side of said key, the outer faces of said studs and flange lying in a plane parallel with that of the opposite side of the key.

19. In a traveling grate, the combination of a transverse grate bar, a series of intermediate fuel-supporting keys arranged side by side on the grate bar, an end key on the grate bar at the end of the series of intermediate keys, and means for securing the end key on the grate bar, comprising a device connected at its lower end to the grate bar and extending upward into loose connection with the end key, and spring means yieldingly opposing movement of said end key under pressure exerted laterally thereon by the intermediate keys.

20. In a traveling grate, in combination, a transverse grate bar, a series of fuel-supporting keys arranged side by side on the grate bar, a removable end key on said grate bar at the end of said series, and means for fastening the end key to the grate bar, comprising a vertical bolt loosely connected at the top to the end key and at the bottom to the grate bar, and a yielding device to permit lateral movement of the end key under pressure thereon.

21. In a traveling grate, a transverse grate bar having a depressed mid portion, means for mounting fuel-supporting keys side by side in said depressed mid portion, and an end key overlapping the end of the grate bar beyond said depressed mid portion.

22. In a traveling grate, a transverse grate bar having end blocks and an intermediate depressed mid portion, keys mounted side by side in said depressed mid portion and having juxtaposed following aprons forming an ash catcher between adjacent grate bars on their angular separation at the end of the working travel of the grate, the end blocks of said grate bar having corresponding aprons lying in register with those of the intermediate keys.

23. In a traveling grate, a grate bar having a depressed key-supporting web, end blocks between which said web extends, said end blocks having rearwardly extending aprons and corresponding recesses at their forward margins to receive the apron of the adjacent bar in the assembled grate.

In testimony whereof I have signed my name to this specification in the presence of two subscribing witnesses.

WILLIAM LLOYD.
